UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPEWRITING MACHINE.

Application filed July 27, 1920. Serial No. 399,356.

To all whom it may concern:

Be it known that I, CORNELIUS B. CORCORAN, a citizen of the United States, residing in borough of the Bronx, in the 5 county of the Bronx, city and State of New York, have invented certain new and useful Improvements in Typewriting Machines, of which the following is a specification.

This invention relates to line-spacing mechanism, and more particularly to line-spacing mechanism such as is used on the Underwood typewriter, and the invention has for its object such improvement in the 15 construction of these devices that the shock of operation of the parts used in line-spacing is less, resulting in less wear and greater freedom from noise.

A feature of the invention relates to the 20 provision of means whereby the line-space lever is given a movement at each stroke, whether for one, two or three line-spaces, just sufficient to properly line-space the platen, and, for this purpose, means are 25 provided to arrest the line-space lever in various normal positions, said lever moving from any one of these positions to a definite position, such movements corresponding to the movements of the line-space mechanism 30 for effecting one, two or three line-space movements of the platen.

Another feature of the invention relates to the provision of means for controlling the line-spacing slide and pawl, whereby 35 they partake of movements in accordance with the setting of the line-space lever.

A still further feature of my invention relates to the provision for avoiding frictional contact between the line-space slide 40 and the line-space lever during case-shifting movements of the platen, and there is provided for this purpose a clearance between the line-space slide and the line-space lever, said clearance being maintained when 45 the line-space lever is adjusted so as to be arrested in any one of a plurality of normal positions.

Other features and advantages will hereinafter appear.

In the accompanying drawings,

Figure 1 is a top plan view of the left-hand portion of an Underwood typewriter, showing the line-space lever and cooperating line-space mechanism, set for single line-space movements.

Figure 2 is a front elevation of the same.

Figure 3 is an end view of the parts in position for single-space movements of the line-spacing mechanism.

Figure 4 is a somewhat similar view, with 60 parts omitted and with the line-space mechanism set for a two-space movement of the platen.

Figure 5 is a view of the end opposite to Figure 3, showing some of the parts. 65

Referring to the drawings, 1 indicates a platen, having a spindle 2, by which the platen may be rotated in the platen-frame 3, such rotation being effected by means of a ratchet 4, secured to the spindle and adapted to be actuated one, two or three spaces by a pawl 5, pivoted to a line-space or pawl-carrier slide 6. The platen may be rotated, as usual, by hand, by means of a knurled knob 7. The slide 6 is unconnected with but is in the path of movement of and adapted to be engaged and operated by a toe or pawl 8 of a line-space lever or finger-piece 9, the finger-piece being more particularly formed by a forwardly-extending lever-arm of the line-space lever 9, said line-space lever being pivoted at 10 in the carriage-frame 11.

The construction so far described is similar to that usually found in Underwood 85 typewriters, and, with such construction, the line-space lever always has the same amount of motion whether operating for one, two or three steps of line-space movement. 90

In the present construction, I provide means whereby the line-space lever is limited in its movement, depending upon the amount of movement it is desired to give to the line-space pawl. Said lever, in its forward movement, is arrested by a shoulder 12, carried by the carriage-frame, but is limited in its return movement, according to whether one, two or three steps of line-space movement are desired. For 95 this purpose, I provide a settable stop-device comprising a shaft 13, suitably mounted in ears 14, struck up from a plate 15, screwed to the carriage frame, said shaft 13 carrying stop-pins 16, mounted radially about the shaft in angularly spaced relation and so spaced from each other, longitudinally of the shaft, that the line-space lever will be arrested in different positions, according to the rotational position the shaft 110 105 110

occupies. For readily determining the setting of the shaft, an index 16^a, shown as formed on the left-hand ear 14, is provided, the shaft having a pointer 17 co-operating therewith. To conveniently maintain the shaft in its different set positions, a housing 18 is provided on the shaft 13, outside of one of the ears 14, shown as the ear at the right, said housing having a sprung-pressed ball 18^a engaging seats 18^b in the said ear, and shown in Figure 5 and at the right in Figures 1 and 2. The shaft is rotated by a knurled knob 19, secured to its opposite end.

15 A pair of stop-pins 19^a (Figures 1 and 5) on the right-hand ear 14 are engageable by the housing 18 to limit the rotative movement of the pin-carrying shaft 13.

In order that the line-space pawl may 20 operate its ratchet different degrees, the slide 6 carries a pin 20 at its left-hand end, Figure 3, to which is secured a spring 21, the opposite end of said spring being attached to a pin 22, carried by the platen-frame. The spring 21 tends to urge the slide 6 to the right, Figure 3, and towards the toe or pawl 8 of the line-space lever 9, and, to limit the movement of the slide under action of this spring, a settable stop-device is provided comprising a setting lever 23 having a lip 24 extending in front of a pin 25, carried by the slide 6. The lever 23 is also connected by a pin-and-slot connection with a pawl-setting slide 26, which 30 slide carries a shelf 27. The pawl 5 has a portion 28 at one side thereof and which extends rearwardly and downwardly, and normally is seated on the shelf 27 when the pawl is in normal position. With the parts 35 positioned as shown in Figures 1, 2 and 3, movement of the line-space lever will result in engaging and moving rearwardly the slide 6, and, as soon as the portion 28 of the pawl drops off of the shelf 27, the pawl 5 will engage the ratchet 4 and move said ratchet until the parts are arrested by the lever 9 striking the shoulder 12, imparting a single-space movement to the ratchet and platen. If a two-space movement of the 45 ratchet is desired, the lever 23 is moved to the position shown in Figure 4, carrying with it the slide 26, together with the shelf 27, and also, by reason of the fact that the spring 21 is urging the slide 6 forwardly, 50 pressing the pin 25 on the slide against the lip 24 on the lever, said slide will follow up the lever 23 as it is moved from the position shown in Figure 3 to that shown in Figure 4, so that the slide will have a different normal position from that occupied in the Figure 3 position. With the parts 55 thus positioned as in Figure 4, movement of the line-space lever will cause the pawl to acuate the ratchet two spaces, it, of course, being understood that the shaft 13 has been

rotated to position the second pin 16 to contact with the line-space lever, so that it moves from a different normal position from that occupied in Figure 1, and from the position there indicated in dotted lines. 70 It will be noted, in Figure 4, that the pawl 5 drops into engagement with the ratchet after a slight lost motion of the slide, but that this lost motion is the same whether the parts are positioned for one, two or three 75 line-space movements, the amount of movement of the pawl depending upon the setting of the lever 23 and the shaft 13. The slide 26 is maintained in its different positions of adjustment by engagement of a detent 80 spring 29 with depressions 30 in the slide 26, this spring extending from a bearing 31, upon which the slide 26 is slidably supported. Said bearing 31 also forms a pivot for the usual ratchet-detent lever 32, carrying at its 85 end a roller 33, engaging the ratchet-teeth.

It will be noted, by reference to Figure 1, that there is a clearance between slide 6 and the pawl 8, and this clearance is maintained by properly positioning the pins 16 and the 90 depressions in the slide 26, so that the lip 24 always engages the pin 25, to hold the slide out of contact with the pawl 8. This provision is important by reason of the fact that it prevents any frictional contact between the pawl and the slide during case-shifting operations. The mechanism by which case-shifting is performed is not specifically shown, but comprises the usual mechanism for this purpose found in the 100 Underwood typewriter, it being noted that the platen frame 3 is shifted relatively to the carriage-frame 11, under the control of the case-shifting mechanism.

Variations may be resorted to within the 105 scope of the invention, and portions of the improvements may be used without others.

Having thus described my invention, I claim:

1. In a line-spacing mechanism for typewriters, the combination with a platen, of means for moving the platen, comprising a pawl, a line-spacing lever, a pawl-carrier in the path of movement of the line-spacing lever to be operated thereby to impart line-spacing movement to the pawl, means acting through the pawl-carrier for setting the pawl to different positions to control the line-spacing movement of the platen, and means independent of the pawl-setting 110 means for arresting said line-spacing lever in various normal positions spaced to correspond with the setting of said pawl for different line-spacing movements of the platen. 115

2. In a line-space mechanism for typewriters, the combination with a line-space lever, of a slide with which said lever co-operates, said slide being unconnected with but in the path of movement of a part of 120 125 130

5 said lever, a line-space pawl carried by said slide, a spring urging said slide and pawl toward the line space lever, a setting lever having a lip, and a stop carried by said slide and engaging said lip under action of said spring, said setting lever movable to different positions, and said spring acting to cause said slide to follow up said setting lever, whereby said pawl is variably positioned.

10 3. In a line-space mechanism for typewriters, the combination with a line-space lever, of a slide with which said lever cooperates, a line-space pawl carried by said slide, a spring urging said slide and pawl in one direction, a setting lever having a lip, a stop carried by said slide and engaging said lip under action of said spring, said setting lever movable to different positions, 15 and said spring acting to cause said slide to follow up said setting lever, a platen-ratchet engageable by said pawl, a shelf supporting said pawl out of contact with said ratchet when said stop is in contact 20 with said lip, and means for connecting said shelf for movement with said setting lever.

25 4. In a line-space mechanism for typewriters, the combination with a line-space lever, of a slide with which said lever cooperates, a line-space pawl carried by said slide, a spring urging said slide and pawl in one direction, a setting lever having a lip, a stop carried by said slide and engaging said lip under action of said spring, 30 said setting lever movable to different positions, and said spring acting to cause said slide to follow up said setting lever, a platen-ratchet engageable by said pawl, a shelf supporting said pawl out of contact 35 with said ratchet when said stop is in contact with said lip, means for connecting said shelf for movement with said setting lever, and means for stopping said line-space lever in normal positions corresponding to the 40 different positions of said setting lever.

45 5. In a typewriting machine, a carriage, a platen shiftable to enable upper-case characters to be printed, a platen-ratchet, a pawl for actuating said ratchet, means for predetermining the amount of movement of the pawl to actuate the ratchet, a line-spacing lever mounted on the carriage, and means for varying the amount of movement of said line-spacing lever to correspond 50 with the predetermined amount of movement of said pawl, said first means being independent of said latter means and movable relatively thereto in the case-shifting movement of the platen.

60 6. In a typewriting machine, a platen shiftable to cause upper-case characters to be printed, a line-spacing pawl, means for controlling said pawl so that it moves from different predetermined normal positions to a definite position, a line-spacing lever, a

pawl-carrier unconnected with, but in the path of movement of, the line-spacing lever, to be operated thereby, to impart line-spacing movement to the pawl, the said pawl-carrier and line-spacing lever being 70 relatively movable in the case-shifting movement of the platen, and means to set the extent of movement of the line-spacing lever to correspond in spaced relation with the movement of the pawl.

75 7. In a typewriting machine, a carriage, a line-spacing lever mounted on the carriage, means on the carriage for adjustably limiting the stroke of the line-spacing lever, a platen mounted on the carriage and shiftable relatively thereto to permit upper-case characters to be printed, line-spacing mechanism operated by said lever, but shiftable relatively thereto with the platen, comprising a platen-ratchet, a pawl for operating the ratchet, and a pawl-carrier, and means shiftable with the platen for adjusting the position of the pawl-carrier in a corresponding spaced relation with the length of stroke of the line-spacing lever.

80 8. In a typewriting machine, a carriage, a line-spacing lever mounted on the carriage, a platen-frame mounted on the carriage and shiftable relatively thereto to permit upper-case characters to be printed, a platen, line-spacing mechanism operated by the line-spacing lever, but shiftable relatively thereto with the platen, comprising a slide, and separate means on the carriage and on the platen-frame for adjusting respectively the range of movement of the line-spacing lever and the range of movement of the slide to correspond in spaced relation one with the other.

85 9. In a line-space mechanism for typewriting machines, the combination with a carriage-frame and a platen-frame, of means for shifting said platen-frame relatively to said carriage-frame between upper and lower case, a line-space slide mounted on said platen-frame, means for variably positioning said slide to effect different degrees of line-spacing, a line-space lever mounted on said carriage-frame for engaging and actuating said slide, and means for arresting said lever in various normal positions spaced to correspond with the various positions of the slide, said lever and slide being maintained out of contact with each other when the line-space lever is in any one of its normal positions.

10. In a typewriting machine, a platen shiftable to permit upper-case characters to be printed, and mechanism for line-spacing the platen comprising an operating member, a member operated thereby and shiftable relatively thereto in the case-shifting movement of the platen, and means for co-ordinately adjusting the ranges of movement of said members to vary the extent of the line-

- spacing movement of the platen to correspond in spaced relation with one another and prevent lost motion between the members.
- 5 11. Line-spacing mechanism for the platen of a typewriting machine, having, in combination, a line-spacing finger-piece, a ratchet connected with the platen, a pawl engageable with the ratchet, a pawl-carrier unconnected with but in the path of movement of the finger-piece to be engaged and operated thereby to line-space the platen, a spring for returning the pawl-carrier towards the finger-piece, a stop-device settable in the path of the return movement of the finger-piece to vary the extent of such return movement for correspondingly varying the line-spacing of the platen, and a settable stop-device for variably limiting the return movement of the pawl-carrier to correspond with the extent of the return movement of the finger-piece as determined by the settable stop-device therefor.
12. In a front-strike typewriting machine, in combination, a carriage, a platen-frame shiftable on the carriage between upper and lower case positions, a line-spacing finger-piece movably mounted on the carriage, means connected to the platen including a line-space slide on the platen-frame unconnected with but in the path of movement of the finger-piece to be engaged and operated thereby to line-space the platen, a stop-device settable in the path of the return movement of the finger-piece for variably limiting such return movement so as to correspondingly vary the line-spacing of the platen, a spring for returning the slide towards the finger-piece, and a stop-device settable in the path of the return movement of the slide for variably limiting such return movement to correspond with the extent of the return movement of the finger-piece as determined by the settable stop-device therefor, and so as to provide clearance between the returned slide and the returned finger-piece in their various correspondingly returned positions.
13. Line-spacing mechanism for the platen of a typewriting machine, having, in combination, a pivoted line-space lever having a lever-arm forming a finger-piece, and a stop-device settable in the path of movement of said lever-arm to vary the extent of line-spacing movement of the line-space lever for correspondingly varying the line-spacing of the platen; said stop-device comprising a rotatable shaft extending transversely to said lever-arm, and a plurality of stop-pins longitudinally and angularly spaced on the shaft and movable selectively by the rotation of the shaft into or out of the path of movement of said lever-arm.
14. Line-spacing mechanism for the platen of a typewriting machine, having, in combination, a pivoted line-space lever having a lever-arm forming a finger-piece, and a stop-device settable in the path of movement of said lever-arm to vary the extent of line-spacing movement of the line-space lever for correspondingly varying the line-spacing of the platen; said stop-device comprising a rotatable shaft extending transversely to said lever-arm, and a plurality of stop-pins longitudinally and angularly spaced on the shaft and movable selectively by the rotation of the shaft into or out of the path of movement of said lever-arm.
15. Line-spacing mechanism for the platen of a typewriting machine, having, in combination, a pivoted line-space lever having a lever-arm forming a finger-piece, and a stop-device settable in the path of movement of said lever-arm to vary the extent of line-spacing movement of the line-space lever for correspondingly varying the line-spacing of the platen; said stop-device comprising a rotatable shaft extending transversely to said lever-arm, a stop-pin projecting from the shaft and movable into or out of the path of movement of the lever-arm by rotating the shaft, and a detent-device for detaining the pin-carrying shaft at its different rotative positions.
16. Line-spacing mechanism for the platen of a typewriting machine, having, in combination, a pivoted line-space lever having a lever-arm forming a finger-piece, and a stop-device settable in the path of movement of said lever-arm to vary the extent of line-spacing movement of the line-space lever for correspondingly varying the line-spacing of the platen; said stop-device comprising a rotatable shaft extending transversely to said lever-arm, a plurality of stop-pins longitudinally and angularly spaced on the shaft and movable selectively by the rotation of the shaft into or out of the path of movement of said lever-arm, and a detent-device for detaining the pin-carrying shaft at its different rotative positions.
17. Line-spacing mechanism for the platen of a typewriting machine, having, in combination, a pivoted line-space lever having a lever-arm forming a finger-piece, a stop-device settable in the path of the return movement of said lever-arm to vary the extent of the return movement of the line-space lever for correspondingly varying the line-spacing of the platen, a line-space slide unconnected with but in the path of movement of the line-space lever to be engaged and operated thereby to line-space the platen, a spring for returning the slide towards the line-space lever, and a stop-device settable in the path of the return movement of the slide to vary the extent of such return movement to correspond with the extent of the return movement of the line-space lever as determined by the settable stop-device therefor; said stop-device for

the line-space lever comprising a rotatable shaft extending transversely to said lever-arm, a plurality of stop-pins longitudinally and angularly spaced on the shaft and moveable selectively by the rotation of the shaft into or out of the path of the return movement of said lever-arm of the line-space le-

ver, and a detent device for detaining the pin-carrying shaft at its different rotative positions.
